UNITED STATES PATENT OFFICE.

SAMUEL J. McDONALD, OF GALLATIN, MISSOURI.

FARRIERY-MACHINE.

SPECIFICATION forming part of Letters Patent No. 718,271, dated January 13, 1903.

Application filed April 21, 1902. Serial No. 103,931. (No model.)

To all whom it may concern:

Be it known that I, SAMUEL J. McDONALD, a citizen of the United States, and a resident of Gallatin, in the county of Daviess and State of Missouri, have invented new and useful Improvements in Farriery-Machines, of which the following is a full, clear, and exact description.

My invention relates to a machine especially adapted for use by farriers and others in the making of horseshoes; and the primary object that I have in view is the provision of means by which either a plain-toed shoe or a clip-toed shoe may be produced in an easy and quick manner.

A demand exists among farriers for a simple, strong, and compact machine which will hold a horse or mule shoe in a position convenient to the workman in finishing up any portion of a horseshoe, either the plain-toed shoe or the shoe having a toe-clip, and also to finish an outwardly-standing calk at the toe of the shoe, as well as the heel. My improved machine enables these operations to be performed and also allows the heel-calks to be bent and various other kinds of work to be carried on. The machine can be used to such advantage that shoes of better quality and superior finish can be produced, because the shoe retains its full strength and has smooth even surfaces.

Further objects of the invention are to provide for the relative vertical adjustment of the vise-jaws, so as to accommodate different thicknesses of toe-calks and shoes, to secure the parallel relation and movement of the movable jaw at all times to the stationary jaw, to provide improved means for operating the vise by hand or foot power, to enable the working parts to be rotated so as to bring them to any desired or convenient position and also to allow the said working parts to be dismounted and laid aside when not in use, and, finally, to simplify and improve the construction, so as to secure strength and durability and a high degree of efficiency in operation.

Further objects and advantages of the invention will appear in the course of the subjoined description, and the actual scope of the invention will be defined by the claims.

Reference is to be had to the accompanying

drawings, forming a part of this specification, in which similar characters of reference indicate corresponding parts in all the figures. 55

Figure 1 is a side elevation of my improved horseshoe-making machine adapted for use by farriers and others, the vise-jaw being opened and the swaging-die being moved to its inoperative position. Fig. 2 is a sectional elevation showing the vise closed and the swaging-die moved or adjusted to the operative position, the lower part of the machine being partly broken away and in section in order to represent certain features of construction more clearly. Fig. 3 is a plan view, on an enlarged scale, of the upper part of the machine. Fig. 4 is a vertical transverse detail section taken in the plane of the dotted line 4 4 of Fig. 1; and Fig. 5 is a sectional plan through the lower part of the machine, taken in the plane of the dotted line 5 5 of Fig. 1.

In carrying my invention into practice I employ a tubular standard or post 5, which may be of any desired diameter and height, in order to present the operative parts of the improved machine in a position convenient to the blacksmith for use. This post or standard may be mounted or supported by any suitable means, but I prefer to support said post by means which permits it to turn on a vertical axis. One means for accomplishing this end is a base 6, having a collar 7 and an upstanding spindle 8. The base may be of any desired form and size, and it may be secured firmly in place on the floor or to any other surface by approved means. The spindle 8 is of a desired diameter and length to fit snugly in the lower open part of the hollow column or post, and the collar 7 of the base exceeds the internal diameter of said post in order that the lower extremity of the post may bear firmly upon said collar, as shown more clearly by Fig. 2, whereby the end thrust or pressure of the column 5 will be taken up by the annular collar and transmitted to the broad or wide base 6. This construction allows the post and column 5 to turn freely on the base. The end thrust or pressure of the column is absorbed or taken up by said base, and the column, with its contained operating devices, may easily be removed from the base and its spindle when it is not desired to use

the machine, thus allowing the base to remain fixed in place on the floor or other surface, and the machine may be used simply by replacing the column on said base.

5 One of the important features of my invention resides in the employment of an anvil which surmounts the post or column 5 and is disposed to bear directly thereon. This anvil 9 may be of any desired form and size, 10 but, as shown by Fig. 4, I prefer to seat the anvil in a recess or socket 10, which is provided in an anvil-block 11, the latter having a depending stem 12, whereby anvils of different configurations may be used interchangeably in the same anvil-block 11. The stem 12 is fast or integral with the anvil-block and extends below the same in order that the stem may extend well into the hollow column or post, while the anvil-block 11 15 is adapted to rest directly upon the upper extremity of said post. The stem 12 is provided with a series of perforations 13, into either of which may be thrust a pin 14, which lies below the collar or block 15, that is fitted 20 on the stem and is adapted to assist the post in supporting the horizontally-slidable jaw-carrier of the vise. The upper portion of the standard is provided with parallel slots 16, which extend transversely through the 25 standard and lie above the collar or block 15, as shown by Fig. 4, and through these slots pass the members or side portions 17 of the slidable-jaw carrier 18. This jaw-carrier is made or formed of a single piece of 30 metal and is provided with a slot which extends nearly its full length, said slot being indicated at 17^a in Fig. 3 and forming the parallel side members or portions 17, the same adapted to extend loosely through the 35 slots 16 of the hollow column and to lie between the block or carrier 15 and the bottom face of the anvil-block 11. This jaw-carrier is provided at one end with a vertical socket or opening adapted to receive the shank 19 40 of the vise-jaw 20. The jaw-carrier 18 is furthermore provided with a depending guide or brace portion 21, which has its active face disposed in the vertical plane of one side wall of the socket in said jaw-carrier, and 45 against its depending guide or brace 21 is adapted to bear the shank 19 of said vise-jaw. The provision of the shank on the vise-jaw allows the jaw to be raised or lowered with relation to the anvil 9 and the anvil-block 11, and this jaw 20 has one face thereof 50 disposed in coöperative relation to an opposing face of the anvil and the block, thus making these parts coöperate to form the vise. The shank of the movable jaw may be 55 secured adjustably in the jaw-carrier by any suitable means; but, as shown by Figs. 1 and 2, I employ a spring key or wedge 22, which is inserted between the outer face of the jaw-shank 19 and one wall of the socket in the 60 jaw-carrier 18. If desired, however, the well-known equivalent of the wedge may be 65 employed—that is to say, one or more set-

screws may be mounted in the jaw-carrier in position for engagement with the shank 19 of the jaw—and, furthermore, the key 22 and the set-screws just described may both be employed, if desired.

The jaw 20 is considerably wider than its shank 19; but, as shown by Fig. 3, this jaw is not as wide as the anvil-block, although the relative proportions of these parts may be varied.

By referring to Figs. 1 and 2 of the drawings it will be seen that the jaw-carrier 18 is mounted in the slotted upper part of the column for movement or adjustment in a path parallel to the horizontal plane of the anvil, and this jaw-carrier supports the movement of the vise-jaw, which is disposed in a vertical position adjacent and parallel to one of the edges of the anvil or anvil-block. The described arrangement of the parts causes the jaw-carrier to hold the vise-jaw 20 in parallel relation at all times to the anvil, the latter forming the stationary jaw of the vise, and this construction enables the vise to hold the horse or mule shoe in a proper shape while the toe is being welded on, so that the shoe may be perfectly true and level when it is removed from the vise. Furthermore, the jaw 20 or the anvil may be adjusted in a vertical direction, and if the vise-jaw is adjusted it may be tightened to the desired position by the key or wedge 22. This is an important feature of my construction, because the vise-jaw must be raised or lowered to suit the different thicknesses of toe-calks and shoes and at the same time to prevent the shoe during welding of the toe portion thereof from doubling in a backward direction when the toe portion is being finished or when the clip or lip is being formed thereon. If the two jaws met each other in a flat form on top, the shoe would be liable to clench over on the back part thereof, thereby spoiling the shoe and preventing it from properly fitting the animal's foot.

I have also equipped the improved machine with means for adjusting the jaw-carrier and jaw by foot or hand power, and one embodiment of such means is shown in the accompanying drawings as a treadle mechanism, although it is evident that a hand-lever may be employed in lieu of the foot-lever; but these devices are mounted on or supported wholly by the hollow column or post 5, so as to be removable and detachable therewith. A lever 23 is disposed alongside of the standard at the upper part thereof, and this lever is curved to provide a cam-shaped edge 23^a, adapted for engagement by a locking-link 24, to be presently described more fully. This lever is fulcrumed at a point intermediate of its length in the bifurcated end 25^a of a bolt 25, by means of a fulcrum-pin 26, said bolt 25 passing through suitable openings in the standard or post 5 and through one of the openings 13 in the depending stem 12 of the anvil-block 11. (See the dotted lines in Fig.

2 and the full lines in Fig. 4.) The upper short arm of the lever 23 is connected by means of a pivotal bolt 27 to the free ends of the side portions or members 17 of the horizontally-slidable jaw-carrier 18, and this jaw-carrier and the lever are thus operatively connected together in order that the movable vise-jaw may be adjusted or controlled by said lever 23. A spring 28 is arranged to bear against the long arm of the lever 23 in a manner to force said long arm in an outward direction, and thus make the short arm move the jaw-carrier and the jaw away from the anvil-block, said spring 28 being held or confined on the standard or post 5 by the solid part of the head 25^a, which forms a part of the bolt 25.

To the lower end of the actuating-lever 23 is pivoted, as at 29, a draw bar or link 30, which is arranged loosely in a slot which is formed in the post 5 at a point above the spindle 8 of the base, and the other end of this link is pivoted, as at 31, to the upper extremity of a secondary lever 32, said lever being fulcrumed, as at 33, in the bifurcated end 34 of the bolt 35, which passes through the post or column 5 at a point above the extremity of the spindle 8. The foot-treadle 36 is bent to form the arm 36^a, which is pivotally connected, as at 37, to the lower extremity of a carrying-plate 38, said carrying-plate being secured firmly to one face of the standard and receiving the nut on the bolt 35. The angular arm of the treadle is provided with a transverse bolt 39, which receives one end of the pair of links 40, which are disposed on opposite sides of the post 5 and the spindle of the base, as shown by Fig. 5, and the other ends of the links 40 are connected by the bolt 41 to the lower portion of the secondary lever 32, whereby the treadle has operative connection with the lever 32 for the purpose of actuating the levers 32 23 and the link 30 against the energy of the spring 28, thus imparting slidable movement to the jaw-carrier 18 and bringing the vise-jaw 20 into coöperating relation to the anvil.

The treadle 36 carries an adjustable foot-piece 42, which is provided with a clip or band 43, arranged to embrace the treadle and to be held at different points thereon by any suitable form of fastener, such as the key or wedge 44. (See Figs. 1 and 2.)

45 designates a swage-block which is firmly secured to a bent or curved arm 46, the latter being bifurcated, so as to produce the branches 46^a, which have their end portions loosely fitted on the bolt 27, the latter connecting the lever 23 and the slidable jaw-carrier 18, whereby the curved arm of the swage-block is pivotally connected to the jaw-carrier by the same bolt 27 which connects said jaw-carrier and the primary lever 23 together. This swage-block and its curved arm 46 may be turned in an upward direction, so as to make the swage-block overhang the anvil in the position shown by Fig. 2, thus

disposing the swage-block into coöperative relation to the anvil for the purpose of finishing the toe-calk and the upstanding lip 70 or clip on the shoe, as will be understood by farriers. On the other hand, the arm 46 may be turned in a downward direction to assume the position shown by Fig. 1, and the swage-block 45 may thus assume an inoperative relation to the machine, whereby the block is adapted to serve as a support or table for holding a pair of tongs or any other tool.

In using the improved machine the toe is first welded to the shoe and the latter is then placed in the machine, so as to be clamped by and between the anvil and the adjustable vise-jaw. The swage-block is now swung or thrown over and it fits on the face of the toe-calk, so as to finish the toe portion of the shoe by striking with a hammer on the top of said swage-block. This swage imparts a nice smooth finish to the toe and saves the top edge of the vise-jaw from the blows of the hammer, because the blacksmith is liable to deliver misdirected blows and to strike the vise-jaw. This swage is an important addition to the farriery-machine, because it enables the toe to be finished in a superior manner.

It is evident that the active face of the swage may be of any ornamental character by providing grooves or diamond points on said face, and this pattern-face of the swage will be imparted to the shoe and its calk.

My invention contemplates the employment of different kinds of anvils adapted for welding different sizes of sharp toe-calks to shoes, said anvils being used interchangeably in the anvil-block.

The jaw-carrier is adapted to slide in a straight line below the anvil, and this adaptation makes the movable jaw 20 come up square against the opposing face of the anvil-block. This is an advantageous feature, because it prevents the top face of the vise from cutting into the bottom of the shoe, and thus the bottom of the shoe is left in a perfectly smooth condition, and at the same time the shoe is adapted to be firmly gripped by and between the jaws of the vise.

The ring or link 24 is adapted to be dropped to an operative position, as shown by Fig. 2, wherein it engages with the curved edge 23 of the lever and with the post or column 5, so as to lock the lever against movement and prevent the vise-jaw from having accidental displacement away from the anvil, thereby making the vise firmly grip the work. At the same time the link 24 may be raised on the post to the position indicated by dotted lines in Fig. 1, said link being held in its inoperative position by the nut on the bolt 25, that supports the primary lever 23.

It is evident that the active faces of the anvil 9 and the swage-block 45 may be smooth and straight, as shown by the drawings, or that any desired form or contour may be given thereto—as, for example, said parts may

have corrugated active faces adapted to impart an ornamental crimped appearance to the toe or heel calks, as may be desired.

Having thus described my invention, I claim as new and desire to secure by Letters Patent—

1. A machine of the class described, comprising a base, a post or column fitted revolvably thereto, a vise and a treadle connected 10 with said vise to actuate the same, said vise and the treadle being mounted on said post or column and revolvable therewith on the base.
2. In a machine of the class described, the combination with a base and a post or column 15 revolvably fitted thereto and detachable at will therefrom, of a vise, a treadle and operative connections all mounted wholly on said post or column so as to be revolvable and detachable therewith.
3. A machine of the class described, comprising a base having an upstanding spindle and a collar surrounding the spindle at the lower end thereof, a column revolvably fitted 20 to said spindle and resting on said collar of the base, and a vise having treadle-operating means supported wholly by said column.
4. In a machine of the class described, the combination of a single post or column adjustable on a vertical axis, an anvil on the 25 head of the column, a jaw-carrier slidably fitted in said column below the anvil, a vertical jaw mounted in said carrier for horizontal adjustment therewith and disposed in cooperative relation to the anvil, and jaw-adjusting means mounted on the column and connected with the carrier.
5. In a machine of the class described, the combination of a post or column, a fixed block 30 therein, an anvil-block secured to the column, a jaw-carrier slidably mounted in the column between the fixed block and the anvil-block, a vise-jaw on said carrier, and means for operating the vise-jaw.
6. In a machine of the class described, the combination of a column, a fixed block therein, an anvil-block seated on the column and having a depending stem secured in the fixed block, a horizontally-slidable jaw-carrier fitted 35 in the standard between the fixed block and the anvil-block, a jaw mounted on the carrier, and means for operating the jaw-carrier.
7. In a machine of the class described, the combination of a column, an anvil thereon, a jaw-carrier slidably mounted on the column, a vise-jaw on the carrier, a lever fulcrumed 45 on the column and pivoted to said jaw-carrier, an operating device, and a secondary lever also fulcrumed on the column and connected to the first-named lever and the operating device.
8. In a machine of the class described, the combination of a revolvable column, an anvil thereon, a jaw-carrier slidably mounted on

the column and provided with a jaw, a lever 65 fulcrumed on the column and pivoted to the jaw-carrier, a treadle-lever fulcrumed on the column at the lower end thereof, a secondary lever also fulcrumed on the column, and links connecting the secondary lever with 70 the first-named lever and the treadle-lever respectively.

9. A machine of the class described, comprising a post or column, a jaw-carrier, co-operating jaws, a lever pivoted to the jaw-carrier, a spring acting against said lever, a locking device for holding said lever against actuation by said spring, and means whereby the lever may be positively operated.

10. A machine of the class described, having a post or column, a jaw-carrier, co-operating jaws, a lever pivoted to the jaw-carrier, a spring acting against said lever, a link co-operating with the post and said lever and adapted to be lowered to an operative position, and means for operating the lever.

11. In a machine of the class described, the combination with an anvil, of a horizontally-slidable carrier, a jaw on said carrier and disposed in clamping relation to the anvil, an 90 arm pivoted to said carrier and adjustable back and forth therewith and also adjustable over the anvil, and a swage-block carried by said arm and adjustable therewith into overhanging relation to the anvil.

12. In a machine of the class described, the combination of a column, an anvil thereon, a jaw-carrier slidably fitted to the column, a vise-jaw having a shank fitted in the carrier and adjustable vertically thereon, and means 100 for securing the vise-jaw firmly in place on the carrier.

13. In a machine of the class described, the combination of a column, a socketed anvil-block secured thereto, an anvil confined in 105 said socketed block, a jaw-carrier slidably mounted in the column below the anvil-block, and a vertically-adjustable vise-jaw mounted fixedly in the carrier and disposed in co-operative relation to the anvil-block and the anvil 110 therein.

14. A machine of the class described, having a post or column, a jaw-carrier slidably mounted therein and having a socket, an anvil above said jaw-carrier, means for operating the jaw-carrier, a vise-jaw having a shank fitted in the socket of the jaw-carrier and said jaw co-operating with the anvil, and means for firmly clamping the jaw-shank to 115 said jaw-carrier.

In testimony whereof I have signed my name to this specification in the presence of two subscribing witnesses.

SAMUEL J. McDONALD.
